UNITED STATES PATENT OFFICE.

MILLARD H. TURNER, OF WASHINGTON, DISTRICT OF COLUMBIA.

TRUSS.

1,035,500.*

Specification of Letters Patent.

Patented Aug. 13, 1912.

Application filed February 9, 1910. Serial No. 542,969.

To all whom it may concern:

Be it known that I, MILLARD H. TURNER, a citizen of the United States, residing in Washington, in the District of Columbia, 5 have invented certain new and useful Improvements in Trusses, of which the following is a specification.

My invention embodies the advantages of the abdominal support and truss each contributing its beneficial effect to a common end.

The main or primary object of my invention is to suspend the truss from a pliable support suitably secured to an abdominal 15 supporter or other device whereby the supporter or other device may follow the motions of the body without disturbing the truss in its adjusted position; and with this and minor objects in view my invention consists of the parts and combination of parts 20 as will be hereinafter more fully pointed out.

In the drawings:—Figure 1 is a rear elevation of an abdominal band, Fig. 2 is a 25 front elevation of the same embodying my invention, Fig. 3 is a section on the line 3—3 Fig. 2.

The general construction of the abdominal supporter is of the usual character and 30 it consists of the rear portion 1 and the front portion 2, the rear portion having the straps 3 which engage the buckles 4 on the front portion whereby the supporter is firmly secured to the body with the desired 35 degree of tension best adapted to the individual. The stays in the supporter are inserted in the tape pockets 5.

As will be seen from the drawing some of the tapes are wider at the top as at 6 to 40 form a secure foundation upon which to sew suspender buttons 7 to which the ends of a suspender 8 may be fastened. The buttons being fastened to the tape, which extends to the bottom of the supporter, prevent the pull of the suspender distorting 45 the supporter. The usual leg straps 9 are attached at one end to the bottom of the front portion of the supporter near the middle, the free end of each strap being secured 50 in the buckle 10 when the supporter is in position, these straps 9 being tightened to the necessary degree best adapted to the individual case. As will be understood 11 is

a pliable support or strap terminating at its lower end in an enlargement 12 on which 55 a truss pad 13 is secured in any desirable manner. The shape of the pad and the material from which it is constructed are varied according to the individual case. The object of the enlargement 12 on the strap 11 60 is to present an increased area around the truss pad to prevent the pad from presenting an abrupt and sharp edge against which the skin will chafe, besides which the parts immediately around the rupture are more 65 or less supported. The upper end of the strap is passed through the abdominal supporter, which is slotted at 14 for that purpose and engaged by the buckle 15 by means of which the truss-pads are held in the desired 70 adjusted position.

In the drawing I have illustrated my invention as adapted for a double rupture, but of course, it is obvious that a single truss pad may be used. The strap 11 may be of 75 any desired material.

As will be seen from the drawing the truss pads are suspended from the buckles 15 which is the only point of attachment they have to the abdominal supporter and 80 that they are therefore free to be moved pendulum like and adjusted up and down. By reason of this the truss-pads are free to be adjusted over the ruptures and when once placed or adjusted there is no liability 85 of their moving or dragging from over the rupture as a result of any movement of the abdominal supporter in following the movement of the body. That is to say, the truss-pad is not susceptible to the movements of 90 its support.

What I claim is:—

The combination with an abdominal supporter, having slits and buckles secured above said slits of a pliable pendulum support passing through said slits and engaging said buckles, a truss-pad secured to the lower free end of said supports whereby the pad is free to swing pendulum like. 95

In testimony whereof I affix my signature 100 in presence of two witnesses.

MILLARD H. TURNER.
